Attorneys.

Patented Apr. 24, 1925.

1,452,999

UNITED STATES PATENT OFFICE.

HENRY BRIER, OF DARTFORD, ENGLAND.

RECEIVER OF REFRIGERATING-APPARATUS.

Application filed March 9, 1920. Serial No. 364,479.

To all whom it may concern:

Be it known that I, HENRY BRIER, a subject of the King of the United Kingdom of Great Britain and Ireland, and residing at 5 Dartford, England, have invented a certain new and useful Improvement in Receivers of Refrigerating Apparatus, of which the following is a specification.

The invention relates to improvements in 10 receivers for use with refrigerating apparatus employing either ordinary compression or multiple effect compression.

In such apparatus a valve adapted to regulate the inlet of the refrigerating gas or 15 liquefied gas to or the outlet of liquefied gas from the receiver has been controlled by means of a float and a spring in dependence on the quantity of liquid in the receiver. In accordance with my invention I employ a 20 spring loaded lift valve for this purpose.

The invention is illustrated in the accompanying drawing in which Fig. 1 is a vertical section of one embodiment of the invention showing the float assisting to regulate automatically the outlet from the receiver to the evaporator in such manner that an accumulation of liquefied gas may at all times during satisfactory working be retained in the vessel. Fig. 2 shows another embodiment in 25 which a float of displacement or solid type is arranged to assist in regulating automatically the inlet valve to the receiver for the same purpose while Fig. 3 shows a further embodiment having a float of open top can 30 type arranged to assist in regulating the inlet of gas from the condenser to the receiver.

Throughout the several views the same reference numerals indicate similar parts.

With reference to Fig. 1 in which A denotes 40 the receiver arranged as a multiple effect compression receiver, 1 denotes the gas inlet passage to the receiver from the condenser; 2 the gas outlet from the receiver leading to the multiple effect compressor; 45 and 3 the outlet passage for liquefied gas from the receiver to the low pressure evaporator; 4 is a valve loaded partly by a spring 5, the loading of the spring being adjustable from outside the receiver by means of a 50 spindle 6 passing through a stuffing box to a block 11 forming an abutment for the spring, the valve spindle sliding loosely in the block 11. The valve 4 is also loaded by 55 a float 7 within the chamber A, said float being adapted to rise and fall within the chamber and cooperating with levers 9 each

piyoted at one end to an extension of the valve spindle and bearing at the other end on the float. The valve 4 thus assists to govern not only the relative pressures in the 60 evaporator and condenser but also the amount of liquid retained in the receiver. 4' is a valve controlling the inlet of liquefied gas from the condenser, this valve being adjustable by hand by means of the usual 65 block 11' which is moved by the spindle 6' and being shown as loaded by a spring 5'. The loading of the valves 4 and 4' by the springs 5 and 5' is adjusted according to requirements. 8 denotes a spring surround 70 ing the float and arranged to balance to a certain extent the dead weight of the float.

In the embodiment illustrated in Fig. 2, which shows a float of the displacement or solid type arranged to assist in regulating 75 the flow of gas from the condenser to the receiver by controlling automatically the inlet to the receiver from the condenser, the inlet valve spindle extends through the receiver, the valve being partly controlled by 80 the spring 5' and partly by the float 7 acting through levers 9 supported at their adjacent ends in the receiver and pivoted on a collar on the valve spindle, the regulation of the liquefied gas to the evaporator being effected 85 or controlled by the valve 4 which is adjustable by hand and if desired is loaded by a spring.

In the embodiment illustrated in Fig. 3, 90 showing another arrangement for regulating the flow of gas from the condenser to the receiver by automatically controlling the inlet to the receiver from the condenser and employing an open top can type of 95 float, a pipe 10 dipping into the liquid in the float leads the liquid to the outlet to the evaporator. In this arrangement the levers 9 are connected at their outer ends to links 9' attached to the float 7 and are pivoted adjacent to their inner ends to the receiver, their inner ends engaging the inlet valve spindle. In this instance also the regulation of flow of the liquefied gas to the 100 evaporator is effected by a hand controlled valve 4 which is preferably loaded by a 105 spring.

It will be noted that in the three different constructions shown the gas inlet and outlet passages 1 and 2 are located at the upper part of the receiver and that in Figs. 1 and 2 the outlet 3 for the liquefied gas is located at the lower part of the receiver,

while in Fig. 2 the liquid outlet 3 is at the upper part of the receiver and commutes with the liquid through the pipe 10. In each of the different forms shown there is, however, a spring-loaded valve controlled by a float so that the load on the valve is varied in dependence on the quantity of liquid within the receiver.

I claim:

1. In combination, a liquid-containing receiver for use with refrigerating apparatus, said receiver having at its upper part a gas inlet port and a gas outlet port, a spring loaded valve controlling said inlet port, said receiver having also a liquefied gas outlet port, a spring loaded valve controlling said outlet port, a float sustained by the liquid within said receiver, and operative connections between one of said spring loaded valves and said float whereby the load on the valve with which said float is connected is varied in dependence on the quantity of liquid within said receiver.
2. In combination, a liquid containing receiver for use with refrigerating apparatus, said receiver having at its upper part a gas inlet port and a gas outlet port, a spring-loaded valve controlling said inlet port, said receiver having also a liquefied gas outlet port at its lower part, a spring loaded valve controlling said outlet port, a float sustained by the liquid within said receiver, and levers interposed between one of said valves and said float whereby the load on the valve with which said float is connected is varied in dependence on the quantity of liquid within said receiver.

3. In combination, a liquid-containing receiver for use with refrigerating apparatus, said receiver having at its upper part a gas inlet port and a gas outlet port, a spring-loaded valve controlling said inlet port, said receiver having also, at its lower part, an outlet port for the liquefied gas, a float sustained by the liquid within the receiver, means whereby the spring load on said valve may be varied from outside said receiver, and operative connections between one of said valves and said float whereby the load on the valve with which said float is connected is varied in dependence on the quantity of liquid within said receiver.

4. In combination, a liquid-containing receiver for use with refrigerating apparatus, said receiver having at its upper part a gas inlet port and a gas outlet port, and an outlet port for the liquefied gas at its lower part, a float sustained by the liquid within said receiver, spring-loaded lift valves controlling said gas inlet port and said liquid outlet port, and operative connections between said gas inlet port valve and said float whereby the load on said gas inlet port valve is varied in dependence on the quantity of liquid within said receiver.

In testimony whereof I have signed my name to this specification in the presence of two subscribing witnesses.

HENRY BRIER.
